United States Patent Office

Des. 225,043
Patented Nov. 7, 1972

225,043

BELT

Melvin V. Zakarin, 23 Ogden Lane,
Englishtown, N.J. 07726

Filed July 14, 1970, Ser. No. 23,944

Term of patent 3½ years

Int. Cl. D2—07

U.S. Cl. D2—385

Fig. 1.

Fig. 2.

Fig. 3.

FIG. 4.

FIG. 5.

FIG. 6.

FIG. 1 is a front isometric view of a belt, embodying the features of my new design,

FIG. 2 is a front plan view,

FIG. 3 is a rear plan view,

FIG. 4 is a front isometric view of a belt showing another form of my new design,

FIG. 5 is a front plan view, and

FIG. 6 is a rear plan view thereof.

The decorative design shown on FIG. 1 and the modified form shown on FIG. 4 is continuous around the rear and opposite side. Portions of FIGS. 2, 3, 5 and 6 are shown broken away for convenience of illustration.

I claim:

The ornamental design for a belt, substantially as shown and described.
